UNITED STATES PATENT OFFICE

JOSEPH ZUBATY, OF FLINT, MICHIGAN, ASSIGNOR TO A C SPARK PLUG COMPANY, OF FLINT, MICHIGAN, A COMPANY OF MICHIGAN

RESET MECHANISM FOR ODOMETERS

Application filed September 16, 1927. Serial No. 219,973.

My invention relates to odometer mechanism, and particularly to resetting means for moving the trip portion of the odometer back to a zero position; so that the mileage covered by each separate trip may be noted independently of the reading of the total odometer wheels, which register the total distance traveled since the installation of the instrument.

10 More specifically stated, my invention has for its object to provide resetting mechanism in which the member whereby the resetting of the trip odometer is accomplished is more certainly held in its normal position out of engagement with the trip odometer wheels than has heretofore commonly been the case to thereby prevent accidental engagement between the resetting member and the trip odometer mechanism at times when the trip 15 mechanism is not to be reset; and a further object of my invention is to provide resetting mechanism in which looseness between the resetting member and the bearing in which it operates is automatically taken up by means 20 of a suitable spring, thereby preventing vibration of the resetting member when in use upon a vehicle.

With the above and other objects of invention in view my invention consists in the improved trip resetting mechanism for odometers illustrated in the accompanying drawing and hereinafter described and claimed; and in such variations and modifications thereof, within the scope of the concluding 35 claims, as will be obvious to those skilled in the art to which my invention relates.

The drawing accompanying and forming a part of this specification is in the nature of a fragmentary view showing my improved resetting mechanism in connection with odometer mechanism of a type at present in use, the drawing comprising a single figure or view.

In the drawing, the reference numeral 1 designates a suitable frame which is arranged 45 inside a casing 2 of any form, and which frame supports the odometer mechanism illustrated, as well also as speedometer mechanism; my invention being commonly used in connection with an instrument commonly called a "speedometer" and comprising mech-

anism for indicating the speed of the vehicle with which it is used, as well also as for indicating the total mileage traveled and the mileage traveled each trip. The total odometer wheels are indicated by the reference numerals 3, the same being driven from a pinion 4 which in turn is driven from the main driving shaft of the instrument. The numeral 5 designates a shaft which supports the usual carrying pinions 6, as will be appreciated.

60 The wheels of the trip odometer are designated by the numerals 7, three wheels being ordinarily provided; the right hand one indicating tenths of a mile, and the others miles 65 up to one hundred. These trip wheels are supported upon a shaft 8 the ends of which are held in bearings in the frame, and they are rotatable about the shaft as a support in the usual manner. The carrying pinions 9 for the trip odometer are all supported by a single shaft 10 corresponding with the shaft 5 for the total odometer wheels.

65 The reference numeral 11 designates a sleeve which is slidable upon the shaft 8, and the left hand end of this sleeve is in constant driving engagement with the right hand or tenths wheel of the odometer through a slip driving connection at 12. This sleeve is urged toward the right by a spring 13, and the 70 right hand end thereof abuts against the right hand bearing for the shaft 8.

75 The sleeve 11 carries a pinion 14 which moves therewith, and which drives the sleeve and, consequently, the trip train; said pinion 80 being adapted to mesh with a driving gear 15 which is driven from the pinion 4. It therefore follows that the trip train is driven from the pinion 4 through the driving gear 15, the pinion 14, the sleeve 11, and the driving connection indicated by the numeral 12. The pinion 14 is normally in engagement with the driving gear 15, at which time the sleeve is in the right hand position shown in full lines; but moves out of mesh with said gear 85 when the sleeve is moved laterally and to the left against the action of the spring 13.

90 The frame 1 is provided with an elongated bearing 16; and the reference numeral 17 designates a resetting member which is slidable 95

100

in said bearing, and is rotatable to accomplish the resetting of the trip train. This member carries a resetting gear 18 at its inner end, and has at its inner extremity a cam member 19 which cooperates with a second annular cam member 20 carried by the sleeve 11, so that inward movement of the resetting member moves the sleeve 11 sidewise and to the left, because of the mutual action of the said cam members.

10 In the act of resetting the trip odometer inward movement of the resetting member 17 will as explained move the sleeve 11 to the left, thus disengaging the pinion 14 from the driving gear 15; the driving connection between the sleeve and right hand wheel of the trip odometer being maintained, however, through the sliding connection 12. Inward movement of the member 17 to the extent of 20 its travel not only moves the sleeve 11 to the left but brings the resetting gear 18 and the pinion 14 into mesh with one another, as indicated by dotted lines; whereupon and upon rotating the resetting member the trip 25 train may be moved backward or forward to zero, as the train as a whole has been disconnected from the driving gear 15 by the movement of the pinion 14 out of mesh with said gear.

30 The reference numeral 21 designates a spring which surrounds the resetting member 17 and acts between the outer end of the bearing 16 and an abutment carried by the member 17, so that the said member is 35 normally held in its outermost position by the spring, with the resetting gear 18 in its inoperative position. The springs 13 and 21 obviously act in opposition to one another when the cam members 19 and 20 are in engagement; and the combined effect of the two 40 springs, more particularly the spring 21, is to yieldably hold the parts fixed in their normally inoperative position and to prevent vibration thereof, as well also as to prevent 45 accidental inward movement of the resetting member 17, such holding of the parts prevents vibration of the resetting member, due to jarring of the vehicle, which vibration would otherwise occur because of a certain 50 amount of necessary looseness between the resetting member and the bearing 16. In the form of my invention shown the abutment for the outer end of the spring 21 is formed by providing a groove 22 in said member and 55 within which groove the outer coil of the said spring 21 lies; and the outer part of the resetting member beyond the outer extremity of the bearing 16 is of substantially uniform diameter, so that the spring 21 may be put in 60 place by slipping it over such outer end until its outer coil snaps into the groove 22.

Having thus described my invention and explained the operation thereof, I claim and desire to secure by Letters Patent:

65 1. In odometer mechanism of the class de-

scribed, a bearing for a resetting member; a rotatable resetting member slidable in said bearing, and the outer part of which member is of substantially uniform diameter beyond the outer extremity of said bearing and to its outer end; a coil spring surrounding said resetting member and acting between said bearing and an abutment upon said member to hold said member outward and in a normally inoperative position; and a resetting gear carried by the inner end of said resetting member.

2. In odometer mechanism of the class described, a suitable frame; a rotatable resetting member slidable in a bearing carried by said frame, and the outer part of which member is of substantially uniform diameter beyond the outer extremity of said bearing and to its outer end; a resetting gear secured to the inner end of said resetting member; and a coil spring surrounding said resetting member and the outer end of which lies within a groove in said member, and the inner end of which acts against the outer end of said bearing to thereby hold said member and gear in a normally inoperative position.

90 In testimony whereof I affix my signature.
JOSEPH ZUBATY.
